The ornamental design for a single line communications terminal, as shown and described.

DESCRIPTION

FIG. 1 is a front view of an unassembled single line communications terminal to illustrate details of the three component parts of the terminal, from left to right in the figure, a terminal device, a holder, and a display, showing my new design;

FIG. 2 is a rear view of the components shown in FIG. 1; FIG. 3 is a top side view of the components shown in FIG. 1;

FIG. 4 is a bottom side view of the components shown in FIG. 1;

FIG. 5 is a right side view of the components shown in FIG. 1;

FIG. 6 is a left side view of the components shown in FIG. 1;

FIG. 7 is a perspective front view of the unassembled components shown in FIG. 1;

FIG. 8 is a perspective rear view of the unassembled components;

FIG. 9 is a perspective right side view of the components shown in FIG. 7;

FIG. 10 is a perspective right side view of the components shown in FIG. 8;

FIG. 11 is a perspective left side view of the components shown in FIG. 8;

FIG. 12 is a perspective front view of an assembled single line communications terminal condition; and,

FIG. 13 is a perspective rear view of the assembled single line communications terminal.

The components have been shown separated in FIGS. 1-10 for the convenience of the illustration.
